UNITED STATES PATENT OFFICE.

ISAAC W. LITCHFIELD, OF WARWICK, NEW YORK.

DESIGN FOR ZINC FOR ELECTRIC BATTERIES.

SPECIFICATION forming part of Design No. 16,492, dated January 26, 1866.

Application filed October 22, 1885. Serial No. 180,680. Term of patent 14 years.

To all whom it may concern:

Be it known that I, ISAAC W. LITCHFIELD, of Warwick, in the county of Orange and State of New York, a citizen of the United States, 5 have invented and produced a new and original Design for Zines for Electric Batteries, of which the following is a full, clear, and exact description, reference being had to the accompanying drawings, forming a part of this specification, in which—

Figure 1 represents an elevation thereof; Fig. 2, a section upon the line xx of Fig. 1, and Fig. 3 a section upon line yy of Fig. 1.

The design relates to a zinc for galvanic batteries, and its leading feature comprises the conical section extending from near the top to the lower end thereof, the larger diameter or cross section of the conical portion being uppermost, or, in other words, the cone 15 tapering downward instead of upward. The zinc therein shown is represented as circular

in form, having the largest diameter at the point x , and from there gradually tapering to the end y . The section a , above the enlarged portion, is reduced in size to form the neck 25 or arm. It will be seen that the lower tapering section of the zinc is connected with the upper straight section by a section resembling a reversed short frustum of a cone.

Having thus fully described my invention, 30 I claim and desire to secure by Letters Patent of the United States—

A design for a zinc for electric batteries, comprising the lower tapering section, a reversed short frustum of a cone connecting the 35 tapering section with the upper straight section, and said upper straight section, substantially as shown and described.

ISAAC W. LITCHFIELD.
